PUMP.

1,400,188.

Specification of Letters Patent.

Patented Dec. 13, 1921.

Application filed January 28, 1921. Serial No. 440,739.

To all whom it may concern:

Be it known that I, HARRY S. TOOKER, a citizen of the United States, and a resident of Joplin, in the county of Jasper and 5 State of Missouri, have invented certain new and useful Improvements in Pumps, of which the following is a specification.

This invention relates to pumps and the operating means therefor.

10 An important object of this invention is to provide a pump having novel means whereby the same may be operated at a point remote from the same so that a pump operating apparatus in the form of a steam 15 engine or the like need not be installed with the pump.

The invention forming the subject matter of this application aims also to provide a pump having fluid pressure columns provided with novel means whereby the excess fluid within the column is discharged and whereby the necessary quantity of fluid is maintained in the column so that there will be no lost motion in the operation of the 25 pump.

30 A further object of the invention is to provide a pump which may be operated on the surface of the water or submerged and which may be arranged in a variety of positions or which may be suspended in mid-air as when hanging in the shaft of a mine.

35 A further object of the invention is to provide a pump having its working or moving parts inclosed so as to be protected from damage due to the flying of pieces of 40 rock and so forth as a result of blasting in the mine.

A still further object is to provide a 45 pump of the class described which is light and which therefore may be conveniently transferred from place to place as the occasion requires.

A further object of the invention is to provide a pump which by reason of the absence of vibration need not be chained or anchored to a base.

The invention forming the subject matter of the application aims further to provide a pump of the class described which is reliable, efficient, and cheap to install.

In the accompanying drawings, forming a part of this application and in which like numerals are employed to designate like parts throughout the same,

55 Figure 1 is an elevation of a power trans-

mitting mechanism, parts being shown in section.

Fig. 2 is a sectional view through a check valve embodied in the invention.

Fig. 3 is a fragmentary elevation of the 60 pump, parts being shown in section.

In the drawings, wherein for the purpose of illustration is shown the preferred embodiment of the invention, the numerals 6 and 8 designate a pair of conduits or columns through which a quantity of fluid is adapted to pass back and forth under pressure for operating a pump to be later described. As illustrated in Fig. 1 the upper portions of the conduits 6 and 8 have connection with elbows 9 and 10 which are in turn connected to nipples 11 by means of the usual flanges 12. The nipples 11 have connection with the T-coupling 14. The couplings 14 have connection with a pair of 70 aligned cylinders 15 within which pistons 16 reciprocate for the purpose of moving the liquid within the columns 6 and 8 back and forth whereby to operate the aforesaid pump. The pistons may be of any desired 75 type and are connected by a piston rod 18 having its intermediate portion formed with a pair of shoulders or flanges 20 between which an operating device 22 is arranged.

80 The operating device 22 may be the power transmitting member of a steam or other engine and is operated to reciprocate the piston rods 18 whereby the pistons 16 are reciprocated within the cylinders 15. The power 85 transmitting mechanism which includes the cylinders 15, the pistons 16 and associated elements is of course constructed separately from the power plant to which the arm 22 is connected and in fact the power transmitting 90 mechanism is in the nature of an attachment for the power generator.

95 In the operation of the improved pump, the columns 6 and 8 must be completely full so that there will be no lost motion or lack 100 of efficiency in the operation of the pistons 16.

To provide the means whereby the columns 6 and 8 will at all times be adequately supplied with fluid, I have connected a relief conduit 26 to each of the T's 14. As illustrated in Fig. 1, the upper end of each conduit 26 is connected to a T 27 which is in turn connected to a fluid supply pipe 29 by means of a connecting pipe 30 in which is interposed a check valve 32. With reference to Fig. 2 110

it will be observed that the check valve 32 has a flap 34 which is swung to its open position when pressure of the fluid in the reservoir 36 rises above the pressure of the fluid in the column 6. However, the shoulder 38 formed within the casing of the check valve prevents the flap 34 from permitting the passage of liquid from the columns to the reservoir. In this manner the columns 6 and 8 are at all times provided with an adequate supply of water or other fluid.

However, should the pressure of the fluid be greater than is required to operate the pump the pressure will back up through the relief conduit and thus open a valve 40, which is connected to the pipe 30. As illustrated in Fig. 1, the valve 40 is provided with a seat normally engaged by a valve head 42 which acts to close the valve. A coiled spring 44 surrounds the stem of the valve head and serves to normally seat the valve head so that no fluid is permitted to pass through the valve. The tension of the spring 44 may be adjusted by a nut 46 threaded in the rear end of the casing. It will be observed also that the adjusting nut 46 forms a guide for the stem of the valve head. When the pressure of the fluid becomes greater than is necessary to operate the pump 30 and when the pressure exceeds the pressure of the spring 44, the valve head 42 will be unseated and will pass up through the adjacent overflow pipe 48 and into the reservoir or storage tank 36.

35 In preparing the transfer member for operation air relief valves 49 connected to the T members 27 are opened so that any air contained within the conduits will pass off through the air relief valve 49.

40 The improved pump includes an intermediate cylinder 50 with which outer cylinders 51 and 52 are aligned. As illustrated in Fig. 3, a coupling 54 is connected to each of the ends of the cylinder 50 by means of flanges 55 and is connected to the inner ends of the cylinders 51 and 52 by means of flanges 56. The cylinders 51 and 52 are connected to the lower portion of the column or conduits 6 and 8 so that fluid pressure within the columns 6 and 8 will act on the pistons 58 within the cylinders 51 and 52.

45 A piston rod 59 is connected to each piston 58 and has its adjacent ends connected to the main piston 60 slidable within the intermediate cylinder 50. The outer cylinders 51 and 52 are less in diameter than the intermediate cylinder 50 and therefore when the pistons 58 and 60 reciprocate together the chambers formed between the same will 55 be varied in size. It will be seen that the pistons 58 and 60 and the cylinders 50, 51 and 52 provide two chambers between the pistons.

60 The pistons 58 are each moved inwardly 65 or toward the cylinder 50 since the pistons

58 are operated solely by the pressure of the water in the columns 6 and 8.

The branches 62 of a suction pipe 63 are connected to the couplings 54 by means of flanges 64. The branches 62 of course have communication with the chambers between the pistons 58 and 60 so that when one of the pistons 58 moves outwardly a quantity of liquid will be drawn into the opposite chamber. The subsequent inward movement of the piston 58 discharges the liquid within the other chamber into the discharge branch 65 of a discharge conduit or pipe 66 which may extend to any suitable point of discharge. A one-way valve 68 is arranged within the coupling 64 and serves to limit the movement of the liquid within the branches 62 to one direction. That is the valves 68 are one way valves and do not permit of the discharge of the water. Coiled 70 springs 70 are employed for normally seating the valves on the ends 72 of the branches.

75 Each coupling 65 is provided with an outlet valve 72 which seats on the end 73 of the coupling and normally closes the opening in the same. However, when the piston 58 moves inwardly, the liquid confined within the chamber is passed through the openings in the coupling and elevates the valve 72 so that the fluid may pass off 80 through the branch 65 and out through the discharge member 66. One outlet valve 72 is of course provided for each and as the water is passed more to the branches 65, the outlet or discharge valve 72 will work opposite to each other. A coiled spring 74 confined between the head of the valve and a cross rod 75 is employed for normally seating the valve. When the piston 58 moves outwardly, the valve 72, is of course closed 85 and the water within the discharge column 62 will not be permitted to enter the chamber.

90 In the use of the improved apparatus, the columns 6 and 8 are connected to the cylinders 51 and 52 so that the reciprocation of the pistons will result in moving the fluid contained within the columns 6 and 8 back and forth. This back and forth movement thus imparted to the fluid within the columns 6 and 8 results in the reciprocation of the pistons 58 so that the fluid will be sucked up through the suction member 63 into the chambers formed between the pistons 58 and 60. When one piston 58 is sucking water into one of the chambers the other piston 58 is discharging the water into one of the discharge branches 55.

95 In starting the improved pump if one of the columns is filled with fluid and the piston for that column advances, a strong pressure will be created which will result in opening of one of the valves 40 so that the excess fluid will overflow into the reservoir 100 105 110 115 120 125 130 135

36 This takes place, however, only in case 130

- the piston 58 operated by the fluid in that column is already in its advanced position. The longitudinal movement of the other piston draws a quantity of fluid from the reservoir through the associated check valve 32 so that a quantity of liquid is supplied to the other column. In this manner an adequate and even supply of fluid is maintained in the columns 6 and 8.
- 10 The pump illustrated in Fig. 3 may be lowered into the shaft of the mine or other place for the purpose of draining the water from the same. The pump operates without being chained or otherwise anchored and 15 without the necessity of providing a seat or mounting for the same. This is accounted for by the lack of vibration. The outward movement of the piston 16 is yieldably limited by a pair of coiled springs 80 which are 20 arranged at the ends of the cylinder.
- As previously stated the pump is located at a point remote from its source of power so that the pump need not be inspected frequently. In fact all parts of the pump are 25 inclosed so that the same are not visible. By inclosing the working parts of the pump, the same are protected from flying stone and the like as a result of blasting mines.
- A number of the improved pumps may be 30 operated from a central power unit, so that power plants may remain stationary while the pumps may be moved from place to place as the occasion requires.
- Having thus described my invention what 35 is claimed is:—
1. An apparatus of the class described comprising a pair of aligned cylinders, aligned pistons arranged in said cylinders, fluid pressure conveyors connected to said cylinders, relief conduits connected to said cylinders, and a reservoir having connection with said relief conduits.
  2. An apparatus of the class described comprising a pair of cylinders, pistons arranged in said cylinders, fluid pressure conveyors connected to said cylinders, relief conduits connected to said cylinders, a reservoir having connection with said relief conduits, and means to operate said pistons.
  3. A pump comprising a cylinder, a piston slidable therein and forming a pair of chambers, suction members connected to said chambers, discharge members connected to said chambers, and yieldable means to limit 55 the movement of said piston.
  4. A pump comprising a cylinder having its ends formed with couplings, a pair of cylinders connected to said couplings in alignment with said first named cylinder, a piston within said first named cylinder, a pair of pistons arranged on opposite sides of said first named piston and arranged within said pair of cylinders, said first and second named pistons being connected, suction members connecting the said couplings, and operating means acting on said pair of pistons.
  5. A pump comprising a cylinder having its ends formed with couplings, a pair of cylinders connected to said couplings in alignment with said first named cylinder, a piston within said first named cylinder, a pair of pistons arranged on opposite sides of said first named piston and arranged within said pair of cylinders, said first and second named pistons being connected, suction members connecting the said couplings, and operating means acting on said pair of pistons.
  6. A pump comprising a cylinder having its ends formed with couplings, a pair of cylinders connected to said couplings in alignment with said first named cylinder, a piston within said first named cylinder, a pair of pistons arranged on opposite sides of said first named piston and arranged within said pair of cylinders, said first and second named pistons being connected, suction members connecting the said couplings, and operating means acting on said pair of pistons.
  7. A pump comprising a cylinder having its ends formed with couplings, a pair of cylinders connected to said couplings in alignment with said first named cylinder, a piston within said first named cylinder, a pair of pistons arranged on opposite sides of said first named piston and arranged within said pair of cylinders, said first and second named pistons being connected, suction members connecting the said couplings, operating means acting on said pair of pistons, and discharge members connected to said couplings.
  8. An apparatus of the class described comprising a cylinder, a piston therein, a fluid pressure conveying member connected to said cylinder, a relief conduit connected to the cylinder, and a reservoir connected to said relief conduit.
  9. An apparatus of the class described comprising a cylinder, a piston therein, a fluid pressure conveying member connected to said cylinder, a relief conduit connected to said cylinder, a reservoir connected to said relief conduit, and a check valve controlling the flow through said relief conduit.
  10. An apparatus of the class described comprising a cylinder, a piston therein, a fluid pressure conveying member connected to said cylinder, a relief conduit connected to said cylinder, a reservoir connected to said relief conduit, a check valve arranged within said relief conduit, and an overflow pipe between said relief conduit and said reservoir.
  11. An apparatus of the class described

comprising a plurality of cylinders arranged in alinement, pistons slidable in said cylinders and having a connecting rod, relief conduits connected to said cylinders, relief valves associated with said relief conduits, and a reservoir having connection with said relief conduits.

12. An apparatus of the class described comprising a plurality of cylinders arranged

in alinement, pistons slidable in said cylinders and having a connecting rod, relief conduits connected to said cylinders, relief valves associated with said relief conduits, a reservoir having connection with said relief conduits, and air relief valves connected to said relief conduits.

HARRY SAMUEL TOOKER.
